18 Claims. (Cl. 120—14.5)

1

The present invention relates to writing implements such as multiple mechanical pencils and the like, and more particularly to writing implements of the class comprising an elongated casing and at least one writing material carrier mounted therein for endwise reciprocation.

According to the invention the casing of the writing implement provides for each writing material carrier a separate passage which is eccentrically arranged with respect to the longitudinal axis of the casing and wherethrough the carrier protrudes in writing position.

The accompanying drawings illustrate by way of example one preferred embodiment of the invention.

Fig. 1 is a general view of a multiple mechanical pencil shown partly in elevation, partly in sectional elevation.

Fig. 1a is an elevation of the upper half of a modified writing material carrier using ink.

Fig. 1b is a plan view of an element shown in edge view in Fig. 1a.

Fig. 1c is an elevation of the lower half of an ink carrying member.

Fig. 2 is a sectional elevation of the upper third of the pencil drawn to a larger scale.

Fig. 3 is a top view of the closing head of the pencil.

Fig. 4 is a sectional elevation of the middle third of the pencil in continuation of Fig. 2.

Fig. 5 is a sectional elevation of the lower third of the pencil in continuation of Fig. 4, and

Fig. 6 is a view from below of the pencil point shown in Fig. 5.

The multiple mechanical pencil illustrated comprises a barrel 1 housing the different writing material carriers and having an upper tubular part 2 and a lower part 3 provided with four slot shaped apertures 4 and terminates in a downwardly directed tip 5. In the lower barrel part 3 there are four eccentric tubular passages parallel to and distributed symmetrically around the barrel axis (Figs. 5 and 6). The outside diameter of the barrel part 3 is reduced over a portion of its length, and at this reduced portion each passage 6 is accessible from the outside through one of the apertures 4 over about 90° of its periphery. Each passage 6 terminates in a hole at the tapering surface of the tip 5 (see Fig. 6). In each passage 6 there is longitudinally guided a tubular movable lead carrier 7 which has almost the length of the barrel 1 and includes a writing lead 8, a lead-holding tube 9, a muzzle tube 10 and a sliding tube 11 which latter is externally knurled and encloses tubes 9 and 10 over

2

fractions of their lengths. The upper end of the barrel 1 is closed by a head 12 (Fig. 2) which has a tubular neck 13 partly inserted in the barrel part 2 and may be axially moved therein. This closing head 12 comprises an outer and an inner cap 14 and 15, respectively, which may be rotated on the neck 13.

To the upper end of the tube 2 is secured a spring clip 16, the fixed end 17 of which is bent over the edge of the tube and engages an axial groove 18 in the exterior surface of the neck 13 in order to lock the same against rotation relative to the barrel 1. In downward direction neck 13 terminates in four axial extensions 19 which are regularly spaced from each other and somewhat radially resilient and each of which has formed thereon an externally projecting nose 20 which engages a downwardly directed shoulder 21 of the inner surface of tube 2 in such a manner that head 12 may only be removed from tube 2 by a strong pull such as will not be exerted in the ordinary use of the pencil. At the free ends of the four extensions 19 there is provided a bottom 19a which is crosslike slotted in conformity with the spaces between the extensions and serves to guide a lead carrier 7 in each slit.

When the lead carriers are in their normal, that is retracted, position, the upper rounded end of each lead-holding tube 9 penetrates through a separate bore 23 in a disc 22 fixed in the neck 13 and contacts the inner cap 15. Each lead-holding tube 9 carries on its upper half a catch ring 24 (Fig. 2), against the lower side of which bears a spiral spring 25 surrounding the tube 9 and having its lower end inserted in a socket 26 (Fig. 4), which is placed upon the conical surface of a support 27 and through which the tube 9 may be moved. The support 27 is a truncated cone provided with four recesses 28 for the passage of the four tubes 9 which are guided thereby in a plane including the barrel axis and the lead carrier axis. The support 27 is mounted on a rod 30 which is fixed in a central bore 29 of the lower barrel part 3 and extends coaxially upwardly into the tube 2 (Figs. 4 and 5). Below support 27 each lead-holding tube 9 carries a shoulder ring 31 against the lower side of which bears a spiral spring 32 which surrounds tube 9 and presses with its lower end upon the upper edge of the sliding tube 11.

The lower end of each lead-holding tube 9 (Fig. 5) forms a collet 33 having several lead-gripping jaws 34 which are circumferentially spaced from each other by axial slits and which are resilient and bendable in planes including the axis of the

tube 9. The jaws 34 are provided with teeth on their insides and having outside surfaces shaped as spherical calottes. The collet 33 is surrounded by a clamping sleeve 35 which, in certain limits, is axially movable relative to the jaws and which has a slight inside taper opening into a stepped enlargement 35a towards the muzzle-tube 10. Preferably, the jaws 34 and the clamping sleeve 35 are made of hardened steel. In order to press the jaws against lead 8 the tapered sleeve 35 is moved downwardly into engagement with the spherical surfaces of the jaws and in order to open the grip of the jaws the sleeve is moved upwardly, so that all the jaws may resiliently recede into the enlargement 35a. At a small distance 10a below the collet 33 the muzzle-tube 10 is fixed in the sliding tube 11 and extends with its externally tapered muzzle 36 beyond the same. The muzzle 36 is axially slotted and has formed internally a passageway 36a for maintaining the lead 8 therein without clearance.

In the tip 5 the barrel part 3 is provided with a central bore 37 whereinto is fitted a point 38 made of very hard material, such as steel, cemented carbides, or jewel, which point may be used for marking or writing on surfaces, especially hard surfaces, wherefor the ordinary leads would not be adapted. The hard point also protects the muzzle against deformations due to shocks or impacts of the tip against hard surfaces. The point or pin 38 is exchangeable and may be rounded at one end and pointed at the opposite end. Above each channel exit 6 the barrel part 3 is provided with a color mark 39 referring to the color of the lead 8 in said channel 6.

In order to move a selected lead carrier 9 from retracted position into writing position, the user of the pencil contacts the corresponding sliding tube 11 with a finger tip through the corresponding aperture 4 and moves it forward against the action of the resetting spring 25. As a result, the socket 26 tends to glide down on the conical supporting surface of the support 27 and to move together with the carrier 7 radially away from the barrel axis. However, a substantial deviation of carrier 7 cannot take place before the upper end of the lead-holding tube 9 travelling down along the inner surface of the neck 13 reaches the gap between the extensions 19. Meanwhile, catch ring 24 travels down along the inside taper of a bushing 40 which is fixed in the barrel tube 2 and provides a downwardly directed shoulder 41 which will engage the catch ring, when carrier 7 is completely deviated. It is to be understood that the movement of carrier 7 is controlled by the slotted bottom 19a of neck 12, the recess 28 of support 27 and the channel 6 in the lower barrel part 3. The engagement of catch ring 24 with shoulder 41 maintains carrier 7 against the action of the tensioned resetting spring 25 in writing position even after the finger tip has been lifted off the sliding tube 11.

By pressing the head 12 of the pencil upon the barrel 1 the lead carrier 7 will be reset from writing position into retracted position. In the gaps between the extensions 19 the edge 42 of the neck 13 is bevelled in such a manner that it contacts, upon downward movement of head 12, the upper end of the lead-holding tube 9 and pushes the carrier 7 towards the barrel axis, whereby catch ring 24 leaves shoulder 41, whereupon, under the resetting action of spring 25, the carrier 7 travels into retracted position, and the tapered muzzle 36 of the carrier is completely retracted into the channel 6. It will be apparent that the head 12

must be pressed down against the action of the resetting springs 25 of the carriers which are in retracted position and tend to restore the head 12 to its lifted position, because the tension of each resetting spring in retracted position of the coordinated carrier is such that the carrier is pressed with its upper end against the inner side of the head 12. If there are several or all carriers simultaneously in writing position they will be retracted all together, when the head is sufficiently pressed down so that all the bevelled edges 42 of the neck 13 move the carriers towards the barrel axis.

The lead carrier 7 may be rotated about its axis by rotating the sliding tube 11 at the aperture 4 by means of a finger tip so that it will be possible, when using the pencil, to reduce or prevent the flattening of the lead point by rotating the same about its axis. In the range of the apertures 4 the external surface of the barrel part 3 is smooth, while the surface of the sliding tube 11 is knurled. When in writing position the tip of the forefinger is pressed partly upon the knurled surface and partly upon the smooth one. This finger tip will successively glide over the smooth surface on account of the ability of the knurled surface to rotate. The gliding motion of the finger tip occurs almost unconsciously and causes a slow rotation of carrier 7 and lead 8 about their axis.

When the lead point of carrier 7 which is in writing position, is worn down the lead 8 may be fed out through the passageway 36a by touching the sliding tube 11 through the aperture 4 and drawing the same together with the muzzle tube 10 backward by about the length of the space 10a between tube 10 and jaws 34 against the action of the spring 32. As the lead 8 is held fast by the jaws 34 the passageway 36a of a tube 10 glides back on the lead 8. Then the upper end of tube 10 contacts the clamping sleeve 35 protruding slightly beyond the jaws 34 and pushes it upward, whereby the jaws 34 recede all at once into the enlargement 35a of the sleeve 35, thus releasing the lead 8. A sudden jerk in opening the jaws 34 is useful in order to detach the jaws completely from the lead and to permit particles it may have splintered off the lead to fall out of the teeth of the jaws. When the sliding tube 11 is released spring 32 will push it forward, whereupon the passageway 36a will carry the lead along until the clamping sleeve 35 is returned by a downwardly directed shoulder 43 of the inner surface of the tube 11 into clamping position, wherein the jaws 34 are again pressed against lead 8.

However, spring 32 is so designed that its pressure alone is insufficient to press the jaws 34 by means of the slightly tapered clamping sleeve 35 sufficiently against the lead to resist to all writing stresses. When the selected carrier 7 is advanced from retracted position into writing position the moving force of the finger acting upon the sliding tube 11 overcomes the tension of resetting spring 25 and acts simultaneously in the direction of an advance of clamping sleeve 35 relative to the jaws 34, whereby the clamping pressure upon the jaws and accordingly upon lead 8 is increased. The resetting spring 25 is so designed that when carrier 7 is advanced beyond its writing position, whereby catch ring 24 departs downward from shoulder 41, the coils of spring 25 will soon be pressed upon one another and the lead-holding tube 9 will thereby be stopped, whereas the sliding tube 11 may be fur-

ther advanced by manual pushing or pulling efforts. This means that the gripping pressure of the jaws 34 against lead 8 may also be affected manually. The resulting advantage is that the gripping pressure of the jaws may be manually adjusted according to the nature of the black lead or colored leads, the hardness of which depends on color and composition and varies in wide limits. Very hard leads such as black leads, require a high gripping pressure, while softer leads, such as green or blue leads, require only a moderate gripping pressure. Besides, the sliding tube 11 could not be moved relative to the lead-holding tube 9 against the action of spring 32 by manual effort through aperture 4 in the manner described above, if the pressure of this spring alone would be sufficiently high to clamp lead 8 securely.

The length of the feeding steps by which lead 8 may be advanced depends on the length of the space 10a between the muzzle tube 10 and the lead-gripping jaws 34 and may be enlarged or reduced by replacing muzzle tube 10 by a muzzle tube the length of which within the sliding tube 11 is shorter or longer, respectively, than tube 10.

If the lead is too thin or there is no lead between the jaws 34 the engagement of a stop ring 44 fixed on the lead-holding tube 9 with a downwardly directed shoulder 45 provided above this stop ring on the inner surface of the sliding tube 11 prevents the clamping sleeve 35 from being pushed entirely beyond the resilient jaws 34.

The lead carrier 7 may be loaded with a lead 8 through the muzzle tube 10 or through the closing head 12 of the pencil. For this purpose, the outer cap 14 has formed therein an eccentric hole 46 at the same distance from the barrel axis as the carriers 7. The inner cap 15 is provided with a similarly arranged hole 47 and further with a boss 48 which projects into a can groove 49 on the underside of the outer cap 14, whereby the relative rotation of cap 14 to cap 15 about the barrel axis is limited to an angle of 90° (Figs. 2 and 3). On the neck 13 there are provided color marks 50 in accordance with position and color of the marks 39 on the barrel part 3. The cylindrical portion of the inner cap 15 covers the color marks 50, but has formed therein a slit 51 wherein, upon rotation of the caps 14 and 15 in counterclockwise direction as seen in Fig. 3, that mark 50 appears which indicates the color of the lead 8 in that carrier 7, above which the bore 47 is located at the moment. When a colored lead 8 is to be filled into the carrier 7 provided for this color, at first cap 14, which may have a knurled edge, will be rotated in counterclockwise direction until the corresponding color mark 50 appears in the slit 51. The hole 47 of the inner cap 15 is then exactly above the upper end of the selected lead-holding tube 9 which will automatically be moved into this hole 47 under the action of the resetting spring 25, but may downwardly recede due to its rounded shape, in case that the hole 47 is rotated further on. In order to establish coincidence between the two bores 46 and 47 the outer cap 14 is then turned in clockwise direction through an angle of 90° whereupon the selected tube 9 will automatically pass with its upper end, under the action of spring 25, through the hole 46 until catch ring 24 is stopped by the bottom 19a. The lead 8 may then easily be inserted into the lead-holding tube 9. Afterwards tube 9 will be returned into the normal position by manipulating the sliding tube 11 and the filling hole in the head 12

will be closed by turning the outer cap 14 in counterclockwise direction through the above-mentioned angle of 90°.

The mechanical pencil described herebefore makes it possible to use leads which are almost as long as the pencil itself. A very short lead piece, once having left the lead-gripping jaws 34, will still be held sufficiently securely in the passageway 36a so that it may be used for writing, and it may be fed out by a subsequent lead which is positioned between the jaws 34.

In case that it is preferred to fill the lead through the muzzle tube 10 into the lead-holding tube 9, it will be useful to provide in the latter a metal pin 61 (Fig. 5) which has about the same diameter as the lead 8 and which has formed at its upper end an enlarged head 62. In usual writing position of the pencil, the pin 61 presses down with its own weight upon the lead and may constitute, consequently, an intermediate member between the lead feeding mechanism and the lead when the latter has left the jaws 34 in order to transmit the feeding action upon that lead. The lead 8 may be used down to the very end and, when it has left the passageway 36a of the muzzle tube 10 the metal pin 61 will appear instead, indicating to the user of the pencil that a new lead must be filled in.

Obviously, in the pencil embodying the principles of the invention, more than one lead carrier 7 may be in writing position at the same time and after a partial rotation of the pencil about its longitudinal axis, in the hand of the user, it will be possible to use one or another of the leads or two leads simultaneously, if desired. When using the pencil in vertical position relative to the writing surface it will be possible to use more than two leads simultaneously.

The lead carriers 7 may occupy a retracted or normal position wherein they are not parallel to the barrel axis, as shown in the drawings, but at a slight inclination relative to said axis.

Of course, there may be more or less than four lead carriers in the barrel, which carriers are eccentrically arranged and manipulated as above described. The marking point 38 of hard material may be omitted.

One or several of the writing material carriers may be adapted for the use of fluid or semi-fluid writing material. In this case, as Figs. 1a, 1b and 1c show, the carrier may comprise two parts, a supporting tube 52 which is similarly designed and has similar functions as the upper half of the lead-holding tube 9, and a tubular container 53 for a semi-liquid writing color 59, for instance, which container is mounted with its closed end on the supporting tube 52 by means of the threads 54 and 55 and which has formed at the opposite end a writing point 57 and the muzzle 58 of the container. A segmental disc 56 at the lower end of the supporting tube 52 prevents the latter from rotating when the container which is exchangeable will be screwed or unscrewed.

Apparently, there may be manufactured writing implements according to this invention which are exclusively equipped with containers for fluid or semi-fluid writing material. However, in practice it will be useful to provide writing implements of the type described which have, for instance, two lead carriers 7 and two ink containers 53, so that it is possible to write by means of one and the same writing implement in two different ink colors and two different lead colors. Besides, in such a writing implement the supporting tubes 52 may be used as containers 60 for

spare leads which could be filled in or removed therefrom through the holes 46 and 47 of the head 12 in the same manner as described in connection with the loading of the lead-holding tubes 9.

What is claimed is:

1. A writing implement comprising a cylindrical barrel including a plurality of tubular passages parallel to and distributed symmetrically around the barrel axis, and, in each of said passages a tubular writing material carrier rotatable in the corresponding passage and axially displaceable therein between a writing position in which its tip projects from the front end of the corresponding passage and a portion thereof near the tip is supported rotatably without substantial play in the lower part of the passage, and a retracted position in which its tip is withdrawn into the barrel.

2. A writing implement comprising a cylindrical barrel including a plurality of tubular passages parallel to and distributed symmetrically around the barrel axis, and, in each of said passages a tubular writing material carrier rotatable in the corresponding passage and axially displaceable therein between a writing position in which its tip projects from the front end of the corresponding passage and a portion thereof near the tip is supported rotatably without substantial play in the lower part of the passage, and a retracted position in which its tip is withdrawn into the barrel, said barrel being provided intermediate its ends with a plurality of slot shaped apertures, one for each passage, the lateral edges of each aperture being disposed in a plane containing a chord of the corresponding tubular passage, whereby part of the outer surface of each carrier is exposed in the corresponding aperture and can be manipulated through said aperture for axial displacement or for rotation in its passage.

3. A writing implement, as claimed in claim 2, in which the lateral edges of each aperture are disposed in a plane containing a chord of the corresponding tubular passage extending at right angles to the radius of said barrel through the center of the corresponding passage and having a length corresponding to about 90° of the periphery of said passage.

4. A writing implement, as claimed in claim 2, in which said slot shaped apertures are formed in the region of the barrel surface on which the tip of the index finger of a person using the implement would rest.

5. A writing implement comprising a cylindrical barrel including a plurality of tubular passages parallel to and distributed symmetrically around the barrel axis, in each of said passages a tubular writing material carrier rotatable in the corresponding passage and axially displaceable therein between a writing position in which its tip projects from the front end of the corresponding passage and a portion thereof near the tip is supported rotatably without substantial play in the lower part of the passage, and a retracted position in which its tip is withdrawn into the barrel, a resetting spring for each carrier acting between a part of the barrel and a part of said carrier to urge the latter into its retracted position, each resetting spring being rotatable with the corresponding carrier, a catch ring on each carrier, a projection on the inner wall of each passage, means to move each carrier upon displacement thereof from its retracted to its writing position to a lock position in which said

projection engages said catch ring and locks the corresponding carrier in its writing position without interfering with its rotation, and manually operated means for disengaging each catch ring 5 from its projection to permit return of the carrier to its retracted position under the force of said resetting spring.

6. A writing implement as claimed in claim 5, in which said means for moving each carrier to 10 its lock position includes an element rigid with said barrel and having an inclined surface, supports for the lower ends of said resetting springs resting slidably on said inclined surface, and each embracing one of said carriers at a point remote 15 from its tip so as to displace a portion of said carrier radially in one direction when said spring is compressed, and said manually operated means includes a cam element for cooperation with a portion of each carrier to move the same positively in the opposite radial direction.

7. A writing implement, as claimed in claim 5, in which said manually operated means includes 15 a closing head reciprocable in the upper end of the barrel and including a cam surface for cooperation with the upper end of each carrier locked in its writing position to disengage the catch ring 20 on said carrier from the projection to which it is locked.

8. A writing implement comprising a cylindrical barrel including a plurality of tubular passages parallel to and distributed symmetrically around the barrel axis, in each of said passages a tubular writing material carrier open at its top, a closing head for said barrel having a rotatable 30 cover portion provided with an eccentric hole at such a distance from the axis of rotation that it can be aligned with each of said carriers, and means for closing said hole.

9. A writing implement, as claimed in claim 8, 35 in which said head includes two superposed caps rotatable relative to the barrel and, at least to some extent, relative to each other, each cap being provided with an eccentric hole arranged in such a manner that said holes can be brought in alignment with each other and with each selected one of said carriers.

10. A writing implement comprising in combination with a barrel provided with a tubular passage a lead carrier axially displaceable in said tubular passage, said lead carrier including a lead holding tube, a sliding tube reciprocable endwise on said lead holding tube, and a muzzle tube rigidly fitted in said sliding tube.

11. A writing implement comprising in combination with a barrel provided with a tubular passage a lead carrier axially displaceable in said tubular passage, said lead carrier including a lead holding tube, a sliding tube reciprocable endwise on said lead holding tube, a muzzle tube rigidly 50 fitted in said sliding tube, said lead holding tube terminating towards the muzzle in lead gripping jaws which are resilient in planes including the axis of the tube, and an inwardly and downwardly tapered clamping sleeve disposed between said 55 jaws and said sliding tubes, said clamping sleeve being axially slideable to a limited extent relative to said lead holding tube and to said sliding tube.

12. A writing implement, as claimed in claim 11, in which said clamping sleeve extends in 60 clamping position towards the muzzle beyond said lead gripping jaws, and said muzzle tube is formed with a shoulder adapted to cooperate with said clamping sleeve in order to move the latter out of its clamping position when said sliding tube 65 is displaced in upward direction.

13. A writing implement, as claimed in claim 11, in which the inward taper of the clamping sleeve opens into a stepped enlargement thereof, which allows the lead-gripping jaws, on displacements of said sleeve in rearward direction, to open simultaneously.

14. A writing implement, as claimed in claim 11, in which said sliding tube is formed with an inwardly projecting shoulder for engaging said clamping sleeve, and a spring operating between said sliding tube and a projection on said lead holding tube urges said sliding tube and with it the clamping sleeve downwardly into clamping position.

15. A writing implement as claimed in claim 11, in which said sliding tube is formed with an inwardly projecting shoulder for engaging said clamping sleeve, and a spring operating between said sliding tube and a projection on said lead holding tube urges said sliding tube and with it the clamping sleeve downwardly into clamping position, the lead holding tube and the sliding tube being provided with cooperating stops to prevent the clamping sleeve from being pushed entirely beyond the lead gripping jaws even if there is no lead held by the said jaws.

16. A writing implement, as claimed in claim 11, in which said muzzle tube has an externally tapered muzzle which is axially slit and has formed internally a passageway for guiding a lead therethrough without play.

17. A writing implement comprising a cylin-

drical barrel including a plurality of tubular passages parallel to and distributed symmetrically around the barrel axis in each of said passages a tubular writing material carrier rotatable in the corresponding passage and axially displaceable therein between a writing position in which its tip projects from the front end of the corresponding passage and a portion thereof near the tip is supported rotatably without substantial play in the lower part of the passage, and a retracted portion in which its tip is withdrawn into the barrel, said barrel having a pointed lower end provided between the exit openings of said passages with a tip of a material the hardness of which exceeds that of the barrel material to protect said openings and to serve as a marking point.

18. A writing implement, as claimed in claim 17, in which said hard tip at the front end of the barrel is formed by a pin which is exchangeably mounted in said barrel.
